UNITED STATES PATENT OFFICE

2,148,220

GUIDE AND DEFLECTOR FOR GLASS CHARGES

James W. Ross, Washington, Pa., assignor to
 Hazel-Atlas Glass Company, Wheeling, W. Va.,
 a corporation of West Virginia

Application December 9, 1936, Serial No. 115,008

5 Claims. (Cl. 49—14)

The invention relates to a device for guiding and deflecting glass charges, and one of the objects of the invention is to provide means for guiding glass charges from a feeder to a forming machine, together with means for deflecting the charges from the forming machine whenever for one reason or another the forming machine is stopped.

Another object of the invention is to provide a device of this character which is easily adaptable to molds of different diameters or of different heights.

A further object of the invention is to provide a deflector in which cooling water or air is automatically admitted when the deflector is moved to operative position.

While the present invention is particularly intended for use with feeders located a considerable distance above the forming machine, such as illustrated in the patent to F. C. Flint, No. 1,764,832, granted June 17, 1930, yet it is to be understood that the invention is equally well adapted to use with feeders located at a conventional distance above a forming machine. Also, of course, the invention is not limited to use with any particular type of feeder, or with any particular type of forming machine.

Various other objects and advantages of the invention will be apparent to those skilled in the art, from the following detailed description, when taken in connection with the accompanying drawings, in which,

Fig. 1 is a side elevational view of the device, in position to deliver charges to the molds.

Fig. 2 is a similar view of the device, but taken from the opposite side.

Fig. 3 is a side elevational view similar to Fig. 1, but showing the deflector moved to position to deflect the charges from the molds.

Fig. 4 is a transverse sectional view of the deflector, taken on line 4—4 of Fig. 3.

Fig. 5 is a detail longitudinal sectional view of an auxiliary guide; and

Fig. 6 is a transverse sectional view thereof, taken on line 6—6 of Fig. 5.

Referring to the drawings in more detail, numeral 1 indicates a pipe which leads vertically downwardly from a glass feeder (not shown) to a point over a rotatable mold table 2 carrying any desired number of molds 3. The main purpose of this pipe, as described in the above-mentioned Flint patent, is to shield the mold charges from air currents while dropping through considerable distances, and to protect the workmen.

Numeral 4 refers to a pipe section which, in the

specific embodiment illustrated, is removably attached to the lower end of the pipe 1, and this pipe section carries the guide and deflector. Numeral 5 refers to a clamp member which is slotted horizontally as indicated by numeral 6, and which is of course split vertically. The upper part of the clamp member is gripped to the lower end of pipe 1 by a lever 7 which has a portion arranged in the lugs 8; and the lower portion of the clamp member is gripped to the pipe section 4 by a bolt 9 arranged in the lugs 10. By operating the lever 7 the entire device, including the clamp member 5 is removed from or attached to the pipe 1; or by operating the bolt 9 the entire device is removed from or attached to the clamp member.

The guide and deflector member, referred to generally by numeral 11, is pivotally attached to the lower end of pipe section 4, as by hinges 12; and as shown in Figures 1 and 2 the joint between the lower end of pipe section 4 and the upper end of the guide and deflector is on a diagonal extending upwardly from the hinge, so that when the guide and deflector is swung to the position shown in Figure 3 there will be ample provision for catching the glass charges in the deflector as they drop from the pipe section. It may be mentioned here that instead of mounting the guide and deflector on the pipe section 4, it may be desirable in some installations to mount it directly on the shield pipe 1; or, where the feeder is not a great distance above the molds, it may be attached to any supporting element below the feeder.

When the guide and deflector member 11 is in vertical position to deliver the glass charges to the molds, there is little contact with the glass charges, and cooling of the member is unnecessary, but when the member is moved to the position shown in Figure 3, to deflect the charges, they slide down the deflecting member, and unless this member were cooled the glass charges would so increase its temperature that they would stick to it. I have therefore provided a water or air jacket 13 on the bottom and side portions of the guide member 11. Nipples 14 and 15 are provided adjacent the upper and lower ends of the jacket. To the upper nipple 14 is attached a stop cock 16 provided with the usual operating valve stem 17, and attached to the valve is a hose or flexible pipe 18 leading from any desired source of water or air. The preferred means for opening and closing the valve will be described hereinafter. If water is used a hose or the like (not shown) may be attached to the lower nipple 15, to carry off the waste water to a drain.

Numeral 19 refers to an auxiliary guide which, if desired, may be mounted on the lower end of the guide and deflector member 11. One of the purposes of this auxiliary guide is to accurately center the mold charges in the molds. That is, various auxiliary guides may be provided, having passages 20 of different diameters, to suit the diameters of molds of various sizes. Thus if the interior diameter of the molds to be used is three inches, an auxiliary guide having a passage of approximately that diameter may be mounted on the guide member 11, thereby assuring an exact centering of the mold charges in the molds.

The glass charges will contact to some extent with the wall of passage 20, and this passage is therefore preferably cooled at all times. For this purpose the auxiliary guide is provided with a water or air cooling jacket 21. Nipples 22 and 23 are provided adjacent the top and bottom of the jacket, and hoses (not shown) are attached thereto to supply the cooling fluid to the lower nipple and carry it off from the upper nipple. The jacket is preferably provided with a vertical partition 24, to cause the cooling fluid to circulate around the jacket.

It is desirable that the auxiliary guide be vertically adjustable, so that it may be properly positioned with respect to molds of different heights. Of course any desired means may be employed for mounting the auxiliary guide for vertical adjustment on the guide and deflector member 11. In the particular embodiment illustrated the auxiliary guide is provided with an upwardly extending hollow stem 25 which is received in the lower end of the guide member, and is gripped in any desired vertical position by operating a lever 26. This lever has a shank portion arranged in lugs 27 on the guide member. A shoulder on the shank portion engages one of the lugs, and the other lug is screw threadedly engaged by the shank portion. Thus by operating the lever the auxiliary guide is clamped in position. Of course the lower portion of the guide member 11 is split to permit this clamping operation.

In normal operation the parts are as shown in Figures 1 and 2, so that the charges delivered by a feeder will drop vertically downward into the molds as they are brought successively into charge receiving position. When the forming machine is to be stopped temporarily and the feeder continued in operation to prevent variation in the temperature and condition of the glass, the guide and deflector member 11 is moved to the position shown in Figure 3, to deflect the charges from the molds to any suitable receiving receptacle. The preferred means for moving the guide between feeding position and deflecting position, and locking it in both positions, will now be described.

Numeral 28 refers to an operating lever keyed to a shaft 29 mounted in lugs 30. Also keyed to the shaft is a lever 31 which is pivotally connected to the upper end of an arcuate link 32; the lower end of the link being pivotally connected to lugs 33 carried by the guide member. With these parts in the positions shown in Figure 1, the guide member is locked in its vertical position by reason of the lever 31 being past the dead center. To move the guide member to its deflecting position, it is only necessary to throw the operating lever 28 to the right (Fig. 1) whereby the linkage will move the guide and deflecting members to the position shown in Figure 3, so that the glass charges will now be deflected from the forming machine to any desired receptacle. The guide

member is locked in this deflecting position by reason of the lever 31 being past dead center, as shown in Figure 3.

When the guide member was in its vertical feeding position it was unnecessary to deliver cooling fluid to the jacket 13, but when it is moved to deflecting position the guide would quickly become overheated, causing the glass to adhere to it, if it were not cooled. It is desirable that cooling fluid be admitted to the jacket 13 just as soon as the guide moves to deflecting position, and it is also desirable that the cooling fluid be automatically admitted, for otherwise it might occasionally be overlooked.

To automatically turn the valve to open position when the guide member is moved to deflecting position, and to automatically close it when the guide member is moved to vertical feeding position, a link 34 is pivotally mounted at one end on the pipe section 4, and its opposite end is pivotally attached to one end of a link 35; the opposite end of this link 35 having a square opening to receive the valve stem 17 which is square in cross-section. Thus when the parts are in the positions shown in Fig. 1, the valve is closed, and when the guide is swung to deflecting position the links 34 and 35 cause the valve stem to be turned to open position. Of course the valve is again closed when the guide member is returned to its feeding position.

From the foregoing description it will be apparent that this simple structure provides means for guiding glass charges from a feeder to a forming machine, and accurately centering the charges in the molds, means for automatically cooling the guide when it is moved to deflecting position, thereby saving in the use of the cooling medium and at the same time assuring proper cooling, means for locking the guide and deflector member in its feeding position and its deflecting position, means for varying the size of the outlet passage by mounting different auxiliary guides on the lower end of the guide and deflector member, and rendering the device adaptable to molds of different heights by the vertical adjustment of the auxiliary guide.

While I have described in detail the specific embodiment of the invention illustrated herein, yet obviously many changes and modifications may be made without departing from the spirit of the invention, and all such changes and modifications are intended to be included within the scope of the appended claims.

What I claim is:

1. An apparatus for delivering glass charges to molds including a deflector member for deflecting charges from the molds, a cooling jacket provided on the member, and means operated by the movement of the member to deflecting position to admit cooling fluid to the jacket.

2. An apparatus for delivering glass charges to molds, including a deflector member for deflecting charges from the molds, a cooling jacket provided on the member, means for moving the member into and out of deflecting position, and means operated by the movement of the member to deflecting position to admit cooling fluid to the jacket.

3. An apparatus for delivering glass charges to molds, including a pivotally mounted guide and deflector member, said member positioned to receive charges from an appropriate source, a cooling jacket provided on the member, said member when in vertical position receiving charges from the source and guiding them to the molds

and when in inclined position receiving charges from the source and deflecting them from the molds, means for moving the member from one position to the other position, and means operated by the movement of the member to inclined position to admit cooling fluid to the jacket.

4. An apparatus for delivering glass charges to molds, including a pivotally mounted guide and deflector member, said member positioned to receive charges from an appropriate source, a cooling jacket provided on the member, a valve controlling the admission of cooling fluid to the jacket, said member when in vertical position receiving charges from the source and guiding them to the molds and when in inclined position receiving charges from the source and deflecting them from the molds, means for moving the member from one position to the other position, a support, and a linkage connecting the valve and said support to open the valve when the member is moved to inclined position and to close the valve when the member is moved to vertical position.

5. An apparatus for delivering glass charges to molds, including a stationary pipe through which the glass charges drop, a pivotally mounted guide and deflector member associated with said pipe, said pipe positioned to receive charges delivered from an appropriate source, said member when in vertical position receiving charges from the pipe and guiding them to molds, and when in inclined position receiving charges from the pipe and deflecting them from the molds, an operating lever pivotally mounted on said pipe, linkage having one end connected with said lever and the other end connected with the guide and deflector member, for swinging the member from one position to the other position, and said linkage being past dead center and abutting the stationary pipe when the member is in inclined position, whereby the member is locked in the inclined position.
